TWIN COMPRESSOR UNIT

Neil B. Spurgeon, River Forest, and James H. Cahill, Wheaton, Ill., assignors to Sears, Roebuck and Co., Chicago, Ill., a corporation of New York

Application February 1, 1937, Serial No. 123,336

4 Claims. (Cl. 230—58)

This invention relates to air compressors of the type used for spraying paint, lacquers and the like, and more particularly to a combination of compressors.

An object of the present invention is to provide a pair of air compressors which are so connected and arranged that they will provide a uniform flow of air with a minimum amount of electrical power consumption.

Another object is to provide a compressor which utilizes two compressor units driven by separate motors and which are so arranged that the motors may be driven from an ordinary house current utilizing the standard fuses and may be started without causing the fuse to blow.

Another object is to provide an air compressor using two compressor units which may be driven separately by two split phase motors so related that the motors may be started for operating the compressors without requiring the use of a mechanical unloading clutch or air unloader.

A further object is to provide an air compressor using two separate compressor units driven by two separate motors, the motors and the units together with the related structure being so connected that the whole may be quickly and reasonably transported and vibration reduced to a minimum.

Other objects and advantages will appear from the following description and the drawing illustrating the invention.

In the drawing:

Fig. 1 is a side elevation of the compressor unit embodying the invention;

Fig. 2 is a top plan view of the structure shown in Fig. 1; and

Fig. 3 is a diagrammatic layout illustrating the relationship between the motors and the controlling switch.

The embodiment selected to illustrate the invention as shown in the drawing comprises a pair of air compressor units 10 and 12 which are mounted on a rectangular base 14 and driven by motors 16 and 18 respectively. The motors 16 and 18 are provided with pulleys 20 which are operatively connected to pulleys 22 of the compressor units by means of belts 24 so that the compressor units may be operated when the motors are operated. The motors 16 and 18 are also secured to the base 14 by any suitable means such as bolts 26.

It will be noted that the motors and the compressors are arranged in tandem relationship so that their respective pulleys will be substantially in the same plane.

As shown in Figures 1 and 2 each of the compressors 10 and 12 comprises a base portion 28 and a head portion 30, which are secured together by screws 32.

5 The compressors 10 and 12, together with the motors 16 and 18, are not, in themselves, the object of the present invention but rather the invention is directed to the novel combination and relationship of these component parts together with the inclusion of certain other elements for providing a compressor having the characteristics set forth hereinbefore. Consequently, different types of compressors and motors per se may be utilized, but for the purpose of the present disclosure and in present practice, it has been found expedient to utilize compressors of the type illustrated and split phase motors.

The compressors 10 and 12 and their top portions are fixedly and rigidly connected by means of a pair of spaced apart connecting plates 34 which are secured to the compressors by means of the bolts 32 used for connecting the heads 30 of the compressors with their respective base portions.

25 The extreme sides of the compressors 10 and 12 are also provided with U-shaped handle portions 36 connected thereto by certain of the bolts 32 so that the unit as a whole may be manually moved from place to place. As shown in Figures 1 and 2, each of the compressors 10 and 12 is provided with an air intake 37 and also with air outlets to which are connected pipes 40 and 42 respectively. The pipe line 42 connects with the pipe line 40 and is provided with a check 30 valve 44 so that air can pass only from the pipe 42 into the pipe 40 and not back towards the compressor 12. The pipe 40 in turn is connected with an expansion chamber 46 which in turn is provided with a pressure indicator 48 and an air hose 50.

45 The rectangular base or carriage 14 on which the above described structure is mounted is preferably formed from sheet steel having the ends and sides bent downwardly at substantially right angles to provide a relatively rigid supporting platform. The rigidity of this platform is further enhanced by provision of a stiffening bar 52 such as an angle bar extending longitudinally on the under side thereof, as shown by dotted lines in Figure 2.

50 As clearly shown in Figure 1, the supporting platform 14 is mounted on rollers or casters 54 so that the carriage may be easily transported. It will be noted that the casters 54 are positioned substantially midway between the compressors

and their respective motors, thereby tending to balance and provide a uniform distribution of the load of the compressor as a unit, thereby reducing any vibration to a minimum which may be set up as a result of the operation of the compressors and the motors.

As shown in Figure 2, a switch 56 is mounted on the platform 14 and is connected with a source of power and the motors 16 and 18 for controlling the operation of the motors.

The wiring diagram illustrated in Figure 3 shows the relationship of the switch to the motors and the power line for successfully controlling the operation of the motors.

The circuit of the diagram illustrated in Figure 3 shows one of the lead-in lines A as being connected with each of the motors 16 and 18 and the other lead-in line B in communication with a switch contact 62. Switch contacts 64 and 66 are in communication with the motor 16. The switch comprises two insulated members 72 and 74 which are rotated simultaneously when the switch knob is turned. The switch member 72 is provided with contacting portions 76 and 78 and the switch member 74 is likewise provided with contacting portions 80 and 82.

Figure 3 shows the relative positions of the rotatable members 72 and 74 when the circuit is open and the motors are not functioning. When it is desired to start the motor 16 for operating the compressor 10, the switch is turned for rotating the members 72 and 74, causing the contact 76 to move into engagement with the contact 68 and the contact 78 to move out of engagement with the contact 64. At the same time the member 74 is rotated the contacts 80 and 82 move out of engagement with the contacts 70 and 66 and into engagement with the contacts 66 and 62 respectively, thereby starting the motor 16 for operating the compressor 10. When the motor 16 and the compressor 10 are operating at full speed the switch knob is again rotated for rotating the members 72 and 74, thereby causing the contacts 76 and 78 of the member 72 to engage the contacts 64 and 68 respectively, and at the same time to rotate the member 74 so that the contacts 80 and 82 will engage the contacts 62 and 10 respectively, thereby starting the motor 18 and the compressor 12, the engagement of the contacts 64 and 68 with the member 72 insuring the continued operation of the motor 16 and compressor 10.

Thus it will be seen that one motor and compressor may be started and allowed to reach its maximum speed before starting the other motor and compressor, which prevents the power line from being overloaded and causing the fuses to blow out such as would happen if the motors were started simultaneously. The motors, of course, could be started simultaneously provided that fuses having a higher capacity were used, but the use of such fuses on low voltage lines results in danger of burning out the motor due to the fact that there is not enough voltage to turn the motor. The over-fusing of the electrical circuit is also dangerous as a fire hazard and further objectionable by reason of the fact that it may cause a flickering of lights in neighboring lines with consequent complaints. The utilization of this circuit for starting the motors separately also enables split phase motors to be utilized which otherwise would not be possible in-

asmuch as such motors have poor starting characteristics.

It will also be noted that when the compressor 10 is in operation prior to the operation of the compressor 12, the pressure of the air from the compressor 10 is prevented from being transmitted to the compressor 12 by reason of the check valve 44 so that the compressor 12 may be started without being subjected to a starting load.

10 Thus it will be seen that a compressor is provided for supplying a stream of air under pressure with a maximum of efficiency, that it is adaptable for use with a low voltage line, and may be quickly and easily moved from place to place. Furthermore, the several members are so arranged and connected that the unit as a whole will offer little, if any, vibration.

We claim:

1. In combination, a platform, a pair of motors, a pair of air compressors mounted on the platform and provided with pulleys, belt means connected with the pulleys of the compressors and the motors whereby the compressors may be operated when the motors are run, said motors and compressors being arranged in tandem and the pulleys thereof disposed substantially in the same plane, and means comprising rollers mounted on the under side of said platform whereby the platform may be transported, said rollers being positioned substantially midway between the compressors and the motors.

2. In combination, a pair of compressors, power means operatively connected with the compressors, each of said compressors being provided with an air inlet opening and an air outlet conduit, an expansion chamber in communication with said air outlet conduits, a check valve connected with one of the conduits for preventing the passage of air from the expansion chamber to one of the compressors when one of the compressors is not in operation and means for so actuating said power means that said other compressor is first placed in operation alone and thereafter said one compressor is placed in operation without stopping said other compressor.

3. In combination, a base, a pair of spaced apart air compressors mounted on the base, power means for operating the compressors, said compressors having conduits connected therewith for providing communication therebetween, each of said compressors comprising a base portion and a head portion, screws for connecting the head portions with the base portions, and a pair of spaced apart plate members disposed between the compressors, said screws being adapted for fixedly connecting the plate members with the compressors for providing a rigid connection therebetween.

4. In combination, a support, a pair of spaced apart independently operated compressors separately mounted on said support and having conduits connected therewith for providing communication therebetween, each of said compressors comprising a base portion and a head portion, means connecting said portions of each compressor together, and rigid connecting means bridging the space between said compressors, the first means fixedly connecting the second means with the compressors for providing a rigid connection therebetween.
